COMBINATION GYMNASIUM, SWING AND TRAMPOLINE FOR CHILDREN'S USE

Samuel M. Highberger, Birmingham, Mich., assignor to Trimble, Inc., Rochester, N.Y., a corporation of New York

Application June 16, 1958, Serial No. 51,369

Term of patent 3½ years

(Cl. D34—5)

FIG. 2

Fig. 1 is a perspective view of a combination gymnasium, swing and trampoline for children's use embodying my new design; and

Fig. 2 is a top plan view of this combination gymnasium, swing and trampoline.

I claim:

The ornamental design for a combination gymnasium, swing and trampoline for children's use, substantially as shown.
